CARTON FEEDING AND FILLING SYSTEM

George B. First and Hans Grotewold, Philadelphia, Pa., assignors to Stokes and Smith Company, Summerdale, Pa., a corporation of Pennsylvania

Application November 16, 1939, Serial No. 304,678

13 Claims. (Cl. 93—6)

Our invention relates to systems for feeding and filling cartons.

In accordance with our invention, cartons are removed from a stack thereof and delivered to a conveyor which transports them through a filling station with control of feed of cartons from the stack to the conveyor effected in dependence upon the amount of filling, in each of the successive cartons, lying between predetermined limits of excess and deficiency; furthermore, aforesaid detector device additionally may control mechanism for ejecting from the conveyor, preferably before they are closed, those cartons whose contents are of improper amounts; more particularly, the conveyor may continue to operate or continue to run notwithstanding aforesaid interruption of feed of cartons thereto and ejection of cartons therefrom, thus to clear itself of, or transport to their proper destination, those cartons which have received sufficient filling.

Further in accordance with our invention, the cartons, while flattened or collapsed, are in succession removed from a stack thereof by a gripper, preferably of the suction type, which so positions them that they are opened, in preparation for filling, by their engagement with abutments on the conveyor; more particularly, the cartons are transferred to pockets or recesses provided on the conveyor by a member reciprocating lengthwise of the stack.

Further in accordance with our invention, upon removal of collapsed cartons from the forward end of the stack, the stack is advanced step by step by mechanism comprising a one-way clutch having an oscillating driving member which for feed of the stack is free to follow the movements of a reciprocating actuator to which it is resiliently coupled, preferably by an elastic fluid, and which driving member is precluded from following aforesaid movements of the actuator by a control member engaged by the forward end of the stack upon arrival of its forward end at a predetermined position.

Our invention further resides in the features of construction, combination, and arrangement hereinafter described and claimed.

For an understanding of our invention, reference is to be had to the accompanying drawings, in which:

Fig. 1, in perspective, illustrates a system for closing and filling cartons;

Fig. 2, in perspective, with parts omitted and with parts broken away, illustrates mechanism

for removing cartons from a stack and opening them;

Fig. 3, in perspective, illustrates mechanism for transferring the open cartons to a conveyor;

Fig. 4, in perspective, with parts omitted and with parts broken away, illustrates stack-feeding mechanism;

Fig. 5, in perspective, illustrates a modification of the carton-transfer mechanism;

Fig. 6, in perspective, with parts omitted and with parts broken away, shows an arrangement for checking the degree or sufficiency of filling of the cartons;

Fig. 7, in perspective, with parts omitted and with parts broken away, illustrates ejector mechanism controlled by the apparatus shown in Fig. 6.

Referring to Fig. 1 which exemplifies operations performed upon cartons by a machine generally of the type disclosed in United States Letters Patent No. 1,527,050 to Delamere et al., the cartons C are, in turn, removed from the stack S by mechanism hereinafter more fully described, and delivered to an endless conveyor comprising a belt 2 (Figs. 6, 7) which passes about the drums 3, 25, Fig. 1, and from which extend blocks 1 forming a series of pockets or recesses for reception of the cartons. As each carton moves beyond the position of carton 2C, Fig. 1, its bottom flaps C1 and C2 are turned upwardly and inwardly, and its flaps C3, C4 are bent upwardly and outwardly so that, as the carton moves toward and beyond the position of carton 4C, Fig. 1, adhesive is applied by the roller AB to the under face of the four flaps.

A preferred arrangement for supplying adhesive to the roll AB, and also to roll AT which, as hereinafter described, applies adhesive to the top flaps C5—C8 of the cartons, is disclosed in our copending application Serial No. 302,806, filed November 4, 1939.

As each carton moves beyond the adhesive-applying roll AB, the flap C3 is turned downwardly and then upwardly into adhesive engagement with flaps C1, C2 and finally the flap C4 is moved into overlying adhesive engagement with panel C3.

Each of the cartons with its bottom thus closed then, in turn, passes through a filling station F for filling by mechanism preferably of the type disclosed and claimed in our copending application Serial No. 302,807, filed November 4, 1939. During passage of the cartons through the filling station, the open upper end of each carton is aligned with a filling snout 4 depend-

ing from the rotating plate 5; at a predetermined position of each carton, a gate 6 supported by plate 5 for movement between a filling snout 4 and its associated measuring flask 7 swings outwardly to allow a charge of filling material within the flask to fall into the carton below it.

As each carton moves beyond the filling station F, the quantity of material in each of them is checked by a device L, hereinafter more fully described, and if the filling in any carton is in error in amount, more particularly insufficient, that carton, preferably at a subsequent position, is ejected from the conveyor by ejector mechanism E, hereinafter more fully described. Preferably, the mechanism for detecting error in quantity of material in the cartons also controls the feeding of cartons from stack S, so that when the device L detects improper amount of filling of cartons, supply of additional cartons to the conveyor 2 is interrupted.

Those cartons which are not ejected from the conveyor 2 continue to move therewith toward the adhesive-applying roll AT which applies a coating of adhesive to their top panels C5-C8 which, prior to arrival of each carton at roll AT, have been bent to the position shown, carton 16C. Thereafter, the flaps C1, C8 of each carton are folded over into adhesive attachment with each other and flaps C5, C6 to form the closed top of the carton.

The completed cartons are diverted from the conveyor belt 2 and turned through an angle of substantially 90° for travel broadside with respect to each other (cartons 22C, 23C, etc.) between belts, not shown, which apply pressure, for suitably long time, to the closed ends of the cartons during their travel to a discharge point. A preferred arrangement for turning the cartons and applying pressure to their ends during setting of the adhesive on the flaps is disclosed and claimed in our aforesaid copending application Serial No. 302,806.

Referring to Fig. 2, the stack of flattened cartons is disposed upon a support or plate 8 with the front end of the stack adjacent a region where the conveyor belt 2 passes about the periphery of drum 25. The knife 9 for entering each flattened carton is adjustably secured, as by nut 10, to member 11 pivotally mounted at 12 to the upper end of the vertically reciprocable bar 13, or preferably, as indicated, to the adjustable extension 13A thereof. The spring 14 between the member 11 and its support 13A biases the knife 9 against the front face of the stack yet permits it to yield when the suction gripper device hereinafter described pulls the end carton of the stack toward the position shown in Fig. 2. When the cartons are of the type shown, with flaps C5, C6 shorter than the flaps C1, C8, the knife 9, for uppermost position of its reciprocating support 13, bears against panel C8 at that region thereof exposed above the shorter flap C6. As the knife 9 descends, it swings the side S1 of the carton in counterclockwise direction, as viewed in Fig. 2, and positively separates the sides S1, S2, S3 notwithstanding any inadvertent bond due, for example, to adhesive which may have been, during manufacture of the flattened carton, squeezed out of the usual seam between the sides S1, S2. This preliminary opening of the carton, which may often be dispensed with, insures opening of the cartons by the mechanism hereinafter described.

The reciprocating bar 13 which supports the knife 9 extends downwardly into the housing 15

for connection, by link 16, to the lever 17 upon which is mounted the cam follower 18 continuously engaged by the periphery of the cam 19 on shaft 20 continuously driven from the drive shaft of conveyor belt 2 at such speed that cam 19 makes one revolution during advance of a carton by belt 2 through a distance corresponding with a distance between the center lines of adjacent cartons.

10 The knife 9 and its support are thus positively moved upwardly; however, the downward movement of the knife is preferably effected by biasing means capable of yielding in event the knife 9 is jammed in its descent, as by improper positioning of the cartons in the stack; for example, if the front face of the stack becomes inclined, the obstruction offered by the stack to the descending knife might seriously damage the mechanism. In the exemplary arrangement disclosed, 15 the downward movement of the knife 9 is effected by spring 21 positioned between the guide 22 extending upwardly from the base of the housing 15 and the adjustable stops or nuts 23 on rod 24 24 which extends through the guide 22 for connection to one end of a chain 25 which passes about small sprocket 26 and is attached thereto. The large sprocket 27, also attached to shaft 28, is connected to one end of chain 29 which passes over an idler sprocket 30 for connection at 31 to the lower end of the reciprocable bar 13. Accordingly, the cam 19 in moving bar 13 upwardly effects compression of spring 21 for storage of a limited amount of energy to be expended in effecting downward movement of knife 9.

20 The cartons are in turn removed from stack S by suction-feed devices 32 attached to the hollow shaft 33 for movement therewith as it is oscillated, in timed relation to conveyor 2, by the cam 34 on shaft 20. The periphery of the cam 34 25 is continuously in engagement with cam follower 35 on lever 36 pivotally mounted at one end upon the pin 37 supported by wall structure housing 15, and at its other end pivotally connected to the link 38 extending to the arm 39 attached to aforesaid hollow shaft 33. The spring 40 connected to link 38 biases the suction devices 32 toward engagement with the end carton of the stack S. At its lower end the hollow shaft 33 is connected, as by hose 41, to a suitable source of suction, such as a suction pump, and intermediate its ends shaft 33 is provided with a relief valve 42, biased to closed position by spring 43, and opened by engagement with a stationary stop structure 44 when the suction devices 32 have 30 removed a carton from the stack.

The opening of valve 42 occurs substantially concurrently with movement of the suction heads 32 in counterclockwise direction by or between the members 45 which serve as stops engaging the removed carton positively to strip it from the suction heads. The leading face of each of the conveyor blocks 1 is serrated to catch or engage the corner or edge of each carton between its panels S2, S3 and so by its movement coacts with the suction heads 32 to open the carton, for subsequent reception of filling, before or as it is transferred into the conveyor pocket.

Conveyor 2 is so timed that substantially concurrently with withdrawal of a carton by the suction feeders 32, a pocket or recess formed by a pair of conveyor blocks 1 is in position to receive the carton. Transfer of the open carton into this pocket or recess is effected by pusher mechanism comprising the horizontally reciprocating bar 46 slidably received by guides, not shown, at-

tached to the housing 15. The bar 46 is connected by link 47 to bell-crank lever 48 pivotally supported from wall structure of housing 15 and connected by a link 49 to crank-pin 50 extending from the face of gear 51 driven by gear 52 on the shaft 20.

For each rotation of shaft 20, bar 46 reciprocates to transfer a carton which has been separated from the end of stack S into an empty pocket of the conveyor 2.

The feed of cartons from stack S may be interrupted at any time, without interruption of operation of the other parts of the machine, by swinging a control handle 57 in clockwise direction from the position shown in Fig. 2, to position a latch 58 in the path of shoulder 59 of the member 60 attached to shaft 33. The angular disposition of member 60 on shaft 33 is such that the latch 58 will ride off shoulder 59 and fall behind it when the suction devices 33 are substantially away from the end of the stack of cartons S; latch 58 therefore restrains the devices 32 from movement by spring 30 toward the stack S. When latch 58 is released, as by return of handle 57 to the position shown in Fig. 2, the spring 40 is effective to reestablish normal operation of the suction heads 32 by cam 34.

Preferably the mechanical connections between the control handle 57 and the latch 58 comprise a toggle formed by the arm 61, attached to the shaft 62 of latch member 58, and the arm 63 pivotally connected to arm 61 and slidable through the hub 64 of the control lever 57. The spring 65 is compressed when the control member 57 is moved in either direction to swing the arms 61, 63 over center to break the toggle; stops 66 and 67 limit movement of the latch member 58 by spring 65 in both directions. When member 58 is in engagement with stop 66, it is substantially away from the member 60 and does not engage member 60, for any angular position thereof, until handle 57 has been moved sufficiently to break the toggle.

When it is desired to interrupt removal of cartons from stack S, the control lever 57 may be operated at any time in a revolution of shaft 20, yet the carton feed will not actually stop until there has been completed the removal and transfer of any carton whose removal from the stack has been initiated.

The control handle 57 may be operated at any time to resume feed of the cartons, but the resumption of feed will not actually begin until the conveyor 2, knife 9, and pusher bar 46, which have continued to operate, assume, with respect to suction heads 32, their proper positions for normal operation.

The latch 58 is also subject to the control of an electromagnetic device 68A whose armature or core member 68B is connected to the knee of the toggle 61, 63 by the link 68. As hereinafter more fully described, the solenoid 68A is energized, when a carton receives insufficient amount of filling material, to move the toggle arms 61, 63 over center and so bias the latch 58 for interruption of the carton feed, as above explained in connection with manipulation of the manually operable control lever 57.

In Fig. 4, there is shown the mechanism for feeding the stack of cartons to position for successive removal of the cartons by the suction-grippers 32. The rear carton of the stack is engaged by a plate 69 supported from the weighted member 70 resting upon and advanced by the chains 71. Preferably the engagement be-

tween the chains 71 and member 70 is merely a frictional engagement afforded, for example, by a facing 72 of sponge-rubber or equivalent material attached to the under face of member 70.

5 The sides of the stack are engaged by guide bars 73 to whose forward ends are attached, as by bolts 74, the adjustable stops 75 whose ends are curved outwardly and away from the face of the end carton of the stack.

10 The stop 76 for engaging the lower edge of the front carton of the stack is adjustably attached to a bracket, not shown, extending from the under face of the plate 8. As shown, stop 76, because of a notch in the then front carton flap C3, clears that flap and engages the then rear flap C4 of the front carton; similarly the yielding stop 77, preferably a roller at the end of spring arm 78, clears the top flap C1, because of a notch therein, and engages the flap C8.

20 The spring arm 78 is adjustably secured, as by screw 79, to a bracket 80 which extends over the top of the stack and to which may be attached a spring member 81 for pressing against the top of the stack, particularly near the front end thereof.

25 As the stack is depleted by the automatic removal of cartons from the front end thereof, additional cartons are added to the rear of the stack by an operator who need simply lift off or slide back the member 70 and insert additional cartons between the plate 69 of member 70 and the rear face of the cartons already in place.

30 Feed of the stack S is effected by the intermittent actuation of the chains 71 which pass over the sprockets 83, 83 on shaft 84 to which is attached the driven member 85 of a ratchet or one-way clutch mechanism; i. e., a clutch effective for rotating driven member 85 during only one direction of rotation of the driving member 86, which driving member 86 is attached to or formed with an arm 82 connected by link 87 to a piston 88 slidable within a cylinder 89 attached to wall structure of housing 15. Piston 90, slid-able within the cylinder 89, is connected by link

35 91 to arm 92 pivoted at 93 to the wall structure of the housing 15 and carrying a cam follower received by cam track 95 of the cam 96 attached to the continuously rotating shaft 20. As piston 90 is moved downwardly, the suction created with-

40 50 in the cylinder 89 causes a follow-up movement of the piston 88. The resultant movement of the driving clutch member 86 in clockwise direction is transmitted by the rollers 98 to the driven clutch member 85.

45 55 Upon upward movement of piston 90, the air within the cylinder 89 is compressed and piston 88 is raised, with consequent movement of the clutch member 86 in reverse direction. This reverse movement of member 86 is not transmitted to the conveyor chains through the clutch rollers 98 and driven clutch member 85. Excess pressure within the cylinder 89 is avoided by a simple relief valve comprising, for example, a light spring member 99 biased by its own resiliency to close a port extending through the piston 88.

50 55 Thus, for each revolution of shaft 20 the conveyor chains 71, 71 advance by a small amount or short step to advance the stack S.

55 The extent to which the conveyor chains are moved for each revolution of shaft 20 can be controlled by adjustment of the stop 100 which engages the member 101 attached to and movable with the driving clutch member 86. The position of stop 100 determines the lowermost position to which piston 88 can be moved by suc-

tion created in cylinder 89; in other words, stop 100 provides means for adjusting the stroke of piston 88, and therefore adjustment of the increment of advance of chains 71, notwithstanding constancy of the length of stroke of piston 90.

Interruption of operation of the stack-feeding chains 71 is controlled by a pivoted latch 102 which can be swung to position its shoulder 103 in the path of member 101 attached to the driving clutch member 86. When latch member 102 is swung in clockwise direction from its position shown in Fig. 4, so to engage member 101, the piston 90 reciprocates idly without effecting corresponding reciprocation of the piston 88. The latch 102 may be controlled automatically in response to arrival of the front carton of the stack at the desired position for its removal by the suction heads 32; for example, in the particular arrangement disclosed, there is provided the feeler 104 attached to shaft 105 and biased, as by a suitably light spring 106, to engage the front of the stack. When the arm 104 by engagement by the front end of the advancing stack is sufficiently moved in opposition to spring 106, the arm 107, attached to shaft 105, effects operation of a switch 108 to energize solenoid 109 whose armature or core 110 is connected by link 111 to arm 112 attached to shaft 113 of aforesaid latch member 102; movement of armature 110 in response to energization of solenoid 109 positions latch member 102 in the path of the extension 101 of the clutch member 86 and so precludes further feed of the stack. The switch 108, though shown conventionally as of the push-button type, preferably is of known type requiring for operation of its contacts only a very small force and an operating member moving through only a few thousandths of an inch.

When switch 108 is opened, the solenoid 109 is deenergized and spring 112A connected between arm 112 and pin 115 is effective to return latch 102 and armature 110 to their positions shown in Fig. 4.

In the modification shown in Fig. 5, the cartons, instead of being directly transferred from the stack S to the conveyor 2, are delivered by the carton-feeding mechanism shown in Figs. 2 and 3 to an intermediate conveyor member comprising a drum 25A having extending therefrom blocks 1A providing recesses or pockets to receive the cartons which travel with the drum 25A until deflected therefrom by a stripper plate 114 which coacts with the members 115 to form a gate through which each carton in turn is forced to pass between the pressing rolls 116, 116 rotating at suitably high speed. As each carton emerges from between the rolls 116, its leading edge or corner is engaged by a block 1 of conveyor 2 moving about the axis of drum 25 so that, as in Fig. 3, by continued movement of the conveyor the carton is opened in the recess or pocket between that block 1 and the preceding block. During their travel with the rotating drum 25A, the cartons are precluded from moving outwardly by the guide bars 54A preferably adjustably attached to support 56A.

In passing from conveyor 25A to conveyor belt 2, the cartons are refolded and flattened to weaken or break the fibres along the edges X, Y, along which they previously, while in stack S, were not folded. It is thus insured the sides of each carton, when formed, will remain substantially at right angles.

This modification is particularly desirable when the cartons after closure of their bottoms are

transferred from conveyor 2 to another machine for filling; when the cartons remain in conveyor 2 for the filling and closing operations shown in Fig. 1, the simpler arrangement shown in Fig. 3 is usually satisfactory for most kinds of cartons.

The device L, Fig. 6, for detecting whether or not the cartons have received proper amount of filling, comprises a disc 117 having a plurality of circumferentially spaced pins 118 extending from one face thereof. Each pin passes through an elongated slot 119 in a feeler member 120 maintained in vertical position by its weighted feeling end 121. From the upper end of each member 120 there extends a member comprising shaft 123 and roller 124 thereon for operating electric switch 135 under circumstances herein-after discussed.

Disc 117 is mounted upon shaft 125 whose opposite ends are respectively received by slides 126 and 127 between which the row of filled cartons is transported by conveyor belt 2. The slide 126 is guided by bracket 128 extending upwardly from the bridge 129 which extends between the conveyor drums 3 and 25. With locking screw 130 released, the slides 126 and 127 may be raised or lowered by adjustment of screw 131 so to predetermine the lowest point of the path of travel of the weighted ends 121 of the members 120. From the lower end of slide 127 extends bar 132 slidably received by bracket 133 which extends beneath belt 134 to the bridge member 129.

Upon the slide 127 is mounted a switch 135 which is closed to energize solenoid 68A of the carton-feed mechanism (Fig. 3) when one of the members 120 enters a carton which is insufficiently filled. The switch 135 which may be of any desired construction is mechanically connected to the member 136 pivotally mounted upon slide 127 and biased by spring 137 into the path of the rollers 124.

Assuming the cartons are in proper amount filled, each of the members 120 as it enters a carton engages the filling to hold roller 124 sufficiently high to prevent its engagement with member 136. When, however, a carton is insufficiently filled (carton C13, Fig. 6), the member 120 which enters it moves downwardly beyond the usual position corresponding with proper amount of filling, so that roller 124 engages member 136 and thereby rocks it sufficiently to effect closure of switch 135. The resulting energization of solenoid 68A, Fig. 3, interrupts the feed of cartons from stack S to the conveyor 2.

To prevent the detector L from repeatedly stopping the feed of cartons when the conveyor pockets passing beneath disc 117 are empty of cartons, as at the beginning of a run for example, there is provided a second switch 138 electrically in series with switch 135 to prevent energization of solenoid 68A by closure of switch 135 in event such closure is due to absence of a carton rather than insufficient or other improper filling of a carton. Switch 138, in the example disclosed, comprises an arm 139 which, when engaged by a carton whose sufficiency of filling is being checked, holds the switch contacts closed in opposition to a biasing spring 140; if no carton is present, spring 140 opens switch 138 and so renders closure of switch 135 ineffective to energize solenoid 68A.

For detecting over-filling or too great an amount of filling, the positions of member 136 and member 124 are relatively reversed, so to

cause member 124 to lift member 136, with switch 135 positioned to be closed by member 136 when so lifted.

In brief, interruption of feed of cartons to the conveyor may be effected in dependence upon any amount of filling either in excess of or less than a predetermined or desired amount of filling.

The detector L may also be utilized to cause removal from the row of cartons of those which are insufficiently filled by control of ejector mechanism E, preferably constructed as shown in Fig.

7. The ejector comprises two members 141, 142 normally to one side of the path of travel of the cartons and mounted to move parallel to each other respectively above and below the belt 2 to engage a carton to be ejected both near its top and bottom.

Intermediate their ends, the members 141, 142 are pivotally connected to arms 143, 144 attached to the vertically mounted shaft 145; at its end more remote from belt 2, member 141 is pivotally connected to arm 146 attached to shaft 147 to which is also attached a bell-crank lever 148 one of whose arms is pivotally connected to ejector member 142 and the other of whose arms is pivotally connected to a rod 149. To shaft 147 is also attached arm 150 carrying a follower 151 for engagement with the cam 152 on shaft 153 timed to make one revolution while conveyor 2 is advancing the cartons through a distance corresponding with the distance between the center lines of a pair of adjacent cartons. Such timing may be effected by suitable gearing between shaft 153 (corresponding with shaft 100 of our aforesaid copending applications) and the drive shaft of conveyor drum 3.

With the parts in their positions shown in Fig. 7, the ejector members 141, 142 are restrained against movement by the powerful spring 154 by engagement of stop member 155, on operating rod 149, with the latch member 156 connected by link 157 to the core or armature 158 of solenoid 159.

As thus far described, so long as latch member 156 remains in the position shown in Fig. 7, spring 154 remains compressed and does not operate ejector members 141, 142. When, however, solenoid 159 is energized by closure of switch 135, Fig. 6, in response to detection of an insufficiently filled carton, latch 156 is moved downwardly, in opposition to biasing spring 160, out of the path of stop member 155 and is locked in its lower position by a second latching member 161 biased to its latching position by spring 162. The ejector members 141, 142, however, do not operate immediately upon energization of solenoid 159; they remain in their retracted position until the insufficiently filled carton has moved beyond the light-weight detector and into the path of ejector members 141, 142, whereupon the fall in cam 152 permits spring 154 abruptly to actuate members 141, 142 and so forcibly eject the improperly filled carton from conveyor 2 through a gap in the side guides 54B.

At or near the end of forward movement of the ejector, the second latch member 161 is released from engagement with latch member 156 by the adjustable stop 163, whereupon latch member 156 is moved by spring 160 upwardly into engagement with the under face of extension 164 of stop member 155 on rod 149. As rod 149 is returned to its original position by the rise of cam 152, latch 156 slides along the under

face of extension 164 and eventually passes beyond the extension 164, whereupon spring 160 effects further upward movement of latch 156 to position predetermined by stop 165.

5 To avoid need for solenoid 159 to overcome the large frictional resistance otherwise existing between the latch 156 and stop 155, the cam 152 throughout the angle A is effective to hold stop 155 slightly away from engagement with latch 156 and it is within this angle that switch 135 of the light-weight detector operates, if at all, to energize solenoid 159.

What we claim is:

1. A system for conveying and filling cartons comprising means for removing flattened cartons from a stack thereof, an endless conveyor cooperating with said means to open the cartons, means for filling the opened cartons during their transport by said conveyor, and means responsive to the amount of filling in an opened carton for interrupting operation of said carton-removing means and ineffective to preclude continued operation of said conveyor.

2. A system for conveying and filling cartons comprising means for removing flattened cartons from a stack thereof, an endless conveyor cooperating with said means to open the cartons, means for filling the opened cartons during their transport by said conveyor, and means responsive to the amount of filling in an opened carton to effect interruption of operation of the carton-removing means during continued operation of said conveyor including means providing for delay of said interruption until completion of removal of a carton from said stack and transfer thereof to said container.

3. A system for conveying and filling cartons comprising means for removing flattened cartons from a stack thereof, a conveyor cooperating with said means to open the cartons, mechanism for filling cartons in transport by said conveyor, an ejector operable to remove cartons from said conveyor, and means responsive to the amount of filling in a carton to effect, during continued operation of said conveyor interruption of operation of said carton-removing means and to effect actuation of said ejector.

4. A system for conveying and filling cartons comprising means for removing flattened cartons from a stack thereof, a conveyor cooperating with said means to open the cartons, mechanism for filling cartons in transport by said conveyor, an ejector operable to remove cartons from said conveyor disposed beyond said filling mechanism, a device disposed between said ejector and said filling mechanism to detect carton fillings of undesired amounts, time-delay means controlled by said device to interrupt operation of said carton-removing means, and time-delay means controlled by said device to effect actuation of said ejector during continued operation of said conveyor.

5. A system comprising a conveyor having recesses to receive cartons, and means for removing flattened cartons from a stack thereof and coacting with said conveyor to effect opening of each carton as it is received by one of said recesses.

6. A system comprising a conveyor having recesses to receive cartons, means for feeding a stack of flattened cartons to position the front end of the stack adjacent said conveyor, angularly oscillating structure for engaging each carton in succession as it becomes the front carton of the stack and for swinging it therefrom, and

structure reciprocating lengthwise of said stack to transfer the cartons from said angularly oscillating structure into successive recesses of said conveyor.

7. A system comprising a conveyor having abutments forming recesses to receive cartons, means for feeding a stack of cartons to position the front end of the stack adjacent said conveyor, structure for engaging each carton as it in turn becomes the front carton of the stack and for moving a corner thereof into the path of one of said abutments to effect opening of the carton, and means for moving each carton, when opened, from said structure into one of said recesses.

8. A system for conveying and filling cartons comprising a conveyor having rigid pocket-forming members, means for removing flattened cartons from a stack thereof, opening them and feeding them to the pockets formed by said members of said conveyor, a filling station, a second conveyor having rigid members forming pockets for receiving cartons from said first conveyor and transporting them to said filling station, and means for collapsing and reversely folding the cartons as they pass from said first conveyor to said second conveyor.

9. A system comprising a conveyor having pockets for transporting open cartons, means for removing flattened cartons from a stack thereof, opening and feeding them to said pockets of the conveyor, and means for collapsing the cartons as they pass from said pockets of the conveyor and for thereafter reversely folding them.

10. A system for opening and conveying cartons comprising an endless conveyor having pocket-forming members extending therefrom, means for removing flattened cartons individually from a stack and holding each of them in turn, with a folded edge in the path of movement of one of said members, for co-action with said members in opening the cartons, and means for transfer-

ring each opened carton from said holding means into the pocket formed by said one of said pocket-forming members and the neighboring pocket-forming member.

5 11. A system comprising two conveyors moving in opposite directions at adjacent portions of their paths of movement, abutments extending from each of said conveyors to define pockets for cartons, means for deflecting cartons from the pockets of one of said conveyors, and means for collapsing the deflected cartons and directing each in turn into an approaching pocket of the other of said conveyors.

15 12. A system comprising a conveyor a portion of whose path is curvilinear, carton-clamping abutments attached to said conveyor in spaced relation along it, means for feeding cartons to bring each in turn with a folded edge thereof in position for engagement by one of said abutments while moving in aforesaid curvilinear portion of said path, and means for moving each of the cartons in turn from said position into the open pocket formed by said one of said abutments and the neighboring abutment.

20 13. A system comprising a conveyor having pockets for receiving cartons, means cyclically operable to remove flattened cartons from a stack thereof and delivering them in turn to successive pockets provided on said conveyor including a carton-gripping member biased toward the end carton of the stack and mechanism positively to move said member away from the stack, and means for interrupting feed of cartons to the conveyor during continued operation of said conveyor comprising a control member operable at any time during a cycle of said carton-removing means, and means for delaying the feed-interrupting effect of said control member until aforesaid cycle is completed.
